UNITED STATES PATENT OFFICE.

LARS CHRISTENSON, OF NEW YORK, N. Y.

METALLIC REVOLVING WINDOW.

SPECIFICATION forming part of Letters Patent No. 722,675, dated March 17, 1903.

Application filed June 27, 1902. Serial No. 113,428. (No model.)

To all whom it may concern:

Be it known that I, LARS CHRISTENSON, a subject of the King of Sweden and Norway, and a resident of New York city, county and State of New York, have invented certain new and useful Improvements in Metallic Revolving Windows, of which the following is a specification.

My invention relates to revolving windows constructed of sheet metal; and the object is to provide more simple, cheaper, and more reliable windows of metallic construction for revolving the sash to facilitate cleaning the outsides, as hereinafter described, reference being made to the accompanying drawings, in which—

Figure 1 is a horizontal section of one of the stiles of the window-frame and one each of the stiles of the sashes. Fig. 2 is a detail of one of the sash-stiles in vertical section on line 1 1 of Fig. 1.

A represents a cross-section of a stile of the window-frame made of sheet metal bent into rectangular form, with vertical grooves or recesses for the sashes and stops, as follows: a represents the groove for the upper sash-stile b, c the groove for the middle stop d, and f the groove for the inner stop g, and between grooves f and c is a rib h, the face 30 of which is flush with the bottom of groove a and is practically the bottom of channel i for the lower sash-stile j, the sides of which groove are sides of the stops d and g, respectively. The sash-stiles are also made of sheet 35 metal bent into the required form of cross-section, which is practically rectangular, with a groove k in the edge coacting with the frame-stile A and a groove l in the opposite edge for reception of the glass pane m. The corners of the inner edge are preferably beveled or equivalently toned down, as at n o, or otherwise.

Instead of arranging the sash-stiles in the grooves a i of the frame in the usual manner I provide a channel-bar q for each sash-stile of equal length thereto and of suitable width to fit closely in the grooves and so as to slide in them, but not quite as deep as the depth of the grooves, and having its median web corresponding in form and coacting with the groove k in the sash-stile, which form is such that with said bar fitted so that it may be

pressed back into the frame-groove lateral movement of the sash, as by turning it on its pivots, will force back said bar, thus making 55 the sash self-releasing from its normal holder. The sash-stile and its bar q are connected together midway of their length by a pivot-stud s, fixedly secured to the sash-stile by a block or frame t, inserted within the stile from one 60 end and riveted to its sides at u as a simple and efficient contrivance for reinforcement of the strength of the sheet-metal stile for holding said pivot. The pivot s extends through channel-bar q and reaches to close 65 proximity of the face of rib h of the frame and near the end passes through a spring-plate v, reaching nearly the length of channel-bar q and having angle end parts w turned toward but not quite reaching to the bottom 70 of the channel of said bar. The "set" of this spring-plate is such that the ends tend to thrust outward of the channel-bar q, and coiled wire springs x are placed between said plate and the bottom of the channel to reinforce 75 this tendency. Around the pivot s is another coiled spring y, against which the plate-spring v is seated and held with considerable tension by a pin z. The said spring-plate bears against rib h and supports the springs for 80 thrusting the channel-bar q and affords movable seats for the springs. The sash-suspending chains a' are connected to these spring-plates v at their upper ends for operating the sash. In this case the connection is by the 85 end link of the chain inserted through a hole in the angle-piece w of the spring-plate v and secured by the spring x, threaded through the link under the angle-piece; but the connection may be made in any other approved way. 90 The lower angle-piece w is suitably formed as to its width for a center stud to the spring, the coils of which surround it for being stayed against lateral divergence.

It will be seen that the ends of the springs 95 v bear against the bottoms of the grooves in the frame-stiles, and thus press the channel-bars q firmly into the grooves of the sash-stiles, and thus prevent the sash from shaking and rattling by the wind and also prevent 100 the wind from blowing through, and the sash can be turned readily on the pivots simply by forcing them so that the bevel or equivalently shaped grooves of the sash acting on the cor-

respondingly-shaped channel-bars will force them back so as to permit the sash to swing, and when the sashes are returned the channel-bars are thrust out again and hold the sash firmly.

- 5 5 The stops *d* and *g* are detachably applied, as in other windows, to enable the sash to be put in place, with the attachments, consisting of the channel-bars *q* and springs, connected.
- 10 10 The sash stiles and rails may be filled with wood, if desired.

It is to be noted that by using channel-bars for the slides carrying the sash the channels afford space for the various springs employed 15 between the channel-bars and the window-frame stile for close contact of the sash and channel-bar, particularly the long flat spring *v*, without special preparation of the channel-bars.

- 15 20 What I claim as my invention is—

1. The combination with the grooved window-frame stiles, and the sash having grooved stiles, of the channel-bars, sliding in the grooves of said frame and fitting the grooves 25 of the sash-stiles, pivot-studs of the sash-stiles whereon said channel-bars are slidably connected, and springs controlling the sliding movements of said bars on said pivots, said springs located in the channels of said bars 30 and said sash-stile grooves and channel-bars being self-releasing by the rotatory movements of the sash.

2. The combination with the grooved window-frame stiles, and the sash having grooved stiles, of the channel-bars, sliding in the 35 grooves of said frame and fitting the grooves of the sash-stiles, pivot-studs of the sash-stiles whereon said channel-bars are slidably connected, spring-plates located in the channel-bars and connected with the pivot-studs, 40 coiled springs on said pivot-studs intermediate of said spring-plates and channel-bars, and the coiled springs at the extremities of the spring-plates, seated on and carried by said plates.

3. The combination with the grooved window-frame stiles, and the sash having grooved stiles, of the channel-bars, sliding in the grooves of said frame and fitting the grooves 50 of the sash-stiles, pivot-studs of the sash-stiles whereon said channel-bars are slidably connected, and springs controlling the sliding movements of said bars on said pivots, said sash-stiles, grooves and channel-bars being self-releasing by the rotatory movements of 55 the sash, and said pivot-studs secured in the hollow sash-stiles by the reinforcing-pieces inserted and riveted therein.

Signed at New York this 19th day of June, 1902.

LARS CHRISTENSON.
